(57) **CLAIM**

The ornamental design for lattice, as shown and described.

DESCRIPTION

FIG. 1 is a front perspective view illustrating my design for a lattice;

FIG. 2 is a back perspective view illustrating my design;

FIG. 3 is an enlarged, partial front view of the lattice showing the portion within area 3 of FIG. 1;

FIG. 4 is a left side view thereof;

FIG. 5 is a right side view thereof;

FIG. 6 is a top view thereof; and,

FIG. 7 is a bottom view thereof.
